(57) **CLAIM**

The ornamental design for a golf club head, as shown and described.

DESCRIPTION

FIG. 1 is a top plan view of a golf club head embodying the inventive design.

FIG. 2 is a rear elevational view thereof.

FIG. 3 is a heel-side elevational view thereof.

FIG. 4 is a toe-side elevational view thereof.

FIG. 5 is a bottom plan view thereof; and,

FIG. 6 is a perspective view thereof.

The broken lines immediately adjacent the shaded area represent the bounds of the claimed design, while all other broken lines are directed to environment and are for illustrative purposes only; the broken lines form no part of the claimed design.
